CLAIM

The ornamental design for a fixing plate for apple cutters, as shown and described.

DESCRIPTION

FIG. 1 is a perspective view of a fixing plate for apple cutters, showing my new design.

FIG. 2 is a front view of FIG. 1.

FIG. 3 is a rear view of FIG. 1.

FIG. 4 is a left side view of FIG. 1.

FIG. 5 is a right side view of FIG. 1.

FIG. 6 is a top view of FIG. 1;

FIG. 7 is a bottom view of FIG. 1; and,

FIGS. 8 and 9 are front views showing how to cut an apple using the fixing plate for apple cutters of FIG. 1.

The broken lines in FIGS. 8 and 9 illustrate the environment and form no part of the claimed design. The broken lines in FIGS. 1-2 and 6-7 illustrate portions of the fixing plate for apple cutters and form no part of the claimed design.

1 Claim, 8 Drawing Sheets
